POWERPLANT TRANSMISSION ROTOR UNIT FOR A HELICOPTER

Peter J. Papadakos, Saint James, N. Y., assignor to Gyro-dyne Company of America, Inc., Flowerfield, N. Y., a corporation of New York

Application January 19, 1955, Serial No. 34,078

Term of patent 14 years

(Cl. D71—1)

Fig. 1 is a perspective view of a powerplant transmission rotor unit for a helicopter, showing my new design.

Fig. 2 is a perspective view of the same taken at an angle of approximately 45° to the view of Fig. 1.

Fig. 3 is a top perspective view with portions of upper rotor blades broken away to show the underlying lower rotor blades.

Fig. 4 is a top plan view of the unit, on a slightly larger scale, with the rotor blades omitted for convenience of illustration only.

I claim:

The ornamental design for a powerplant transmission rotor unit for a helicopter, as shown.
